UNITED STATES PATENT OFFICE.

BERNARD F. MULDOON, OF MOUNTAIN VIEW, NEW JERSEY, ASSIGNOR TO HENRY HYMAN, OF BROOKLYN, NEW YORK.

ELECTRIC CIGAR LIGHTER.

Application filed April 30, 1927. Serial No. 187,782.

This invention relates to an electric cigar lighter than can be attached to any convenient source of electricity so that heat can be developed in a heating coil therein whenever desired. The invention comprises an insulating base with a push plug for closing the circuit when desired. The plug carrying the heating coil can be readily inserted and replaced for repairing or renewal.

10 The invention will be understood from the description in connection with the accompanying drawings, in which Fig. 1 is a vertical section through the device, and Fig. 2 is a section along the line 2—2 of Fig. 1.

15 In the drawings reference character 5 indicates a base of insulating material that may be made of porcelain, for example. It is provided with a shallow recess at the bottom thereof for felt 6, or the like, to prevent the device from scratching surfaces upon which it may be placed. Another recess 8 is provided at the top of the device to receive the plug that carries the heating coil. Longitudinal openings 9 and 10 on 20 opposite sides of the central axis of the device, extend through from the recess 8 to the bottom. A spring contact element 11 is mounted in the opening 9 and a spring contact element 12 is mounted in the opening 10. The lower portion of each contact 11 and 12 extends at right angles to the main body portions thereof, and the extended portion of the contact 12 is provided with a hole 13. An elongated plate 14 of stiff insulating material is provided with a hole 15 and a screw bolt 16 extends through the hole 15 of the insulating plate and the hole 13 of the spring contact 12. This screw bolt 16 extends through the central longitudinal opening 17 through the base 5, and is provided with a nut 18 for retaining the same in place. When the nut 18 is screwed up the plate 14 is drawn up into firm engagement with the extending portions of the spring 25 contacts 11 and 12 so as to press the same against a face of the base 5, in order to secure the contacts in place in the openings 9 and 10.

20 A push pin 19 extends through a hole 20 in the side of the base 5 opposite the contact 12, and is provided with a shoulder 21 to prevent it from passing outwardly through the hole, and its inner end is reduced in size and extends into a hole 22 in the spring contact 12.

The heating plug 25 is provided with a metal cap 26, having a central opening at the top thereof and metal plug contacts 27 are attached to the bottom of the plug 25 by means of screw bolts 28 that pass through the plug and are screwed into screw threaded holes in portions of the contacts 27 that extend at right angles to the main body portion thereof. A heating coil 29 has its opposite ends connected to the screw bolts 28 and a mica disc 30 is inserted between the coil 29 and the cap 26.

A hole 32 may be provided through the flanged portion of the base 5 near the bottom thereof, through which hole the electric cord 33 may be passed with the two wires thereof soldered or otherwise connected to the lower ends of the spring contacts 11 and 12.

I claim:

1. In a cigar lighter, an insulating base 75 having openings therethrough, spring contacts in said openings, a plug having contact elements to contact with said spring contacts and a heating coil between said contact elements, means to maintain said spring contacts in place with one of them normally away from the corresponding contact element, and means to close the circuit through said coil temporarily.

2. In a cigar lighter, an insulating base 85 having openings therethrough, spring contacts in said openings, a plug having contact elements to contact with said spring contacts and a heating coil between said contact elements, means comprising a plate of insulating material to maintain said spring contacts in place with one of them normally away from the corresponding contact element, and means to close the circuit through said coil temporarily.

3. In a cigar lighter, an insulating base 95 having openings therethrough, spring contacts in said openings, a plug having contact elements to contact with said spring contacts and a heating coil between said contact elements, means to maintain said spring contacts in place with one of them normally away from the corresponding contact element, said means comprising a bolt extending into said base, and means to close the 105 circuit through said coil temporarily.

4. In a cigar lighter, an insulating base having openings therethrough, spring contacts in said openings having bent portions to contact with a face of said base, a plug 110

having contact elements to contact with said spring contacts and a heating coil between said contact elements, means to maintain said spring contacts in place with one of them normally away from the corresponding contact element, and means to close the circuit through said coil temporarily.

5. In a cigar lighter, a base of insulating material, recesses in the upper and lower portions of said base with openings connecting said recesses, a heating plug in said upper recess having contacts extending into said openings, spring contacts in said openings and means comprising a flat plate in 10 said lower recess for retaining said spring contacts in place.

15. In a cigar lighter, a base of insulating material, recesses in the upper and lower portions of said base with openings connecting said recesses, a heating plug in said upper recess having contacts extending into 20 said openings, spring contacts in said openings and means comprising a flat plate in said lower recess for retaining said spring contacts in place.

6. In a cigar lighter, a base of insulating material, recesses in the upper and lower portions of said base with openings connecting said recesses, a heating plug in said upper recess having contacts extending into 25 said openings, spring contacts in said openings and means comprising a flat plate in said lower recess for retaining said spring contacts in place.

said openings, spring contacts in said openings and means comprising a flat plate in said lower recess for retaining said spring contacts in place by pressing a portion 25 thereof against the upper side of said recess.

7. In a cigar lighter, a base insulating material, recesses in the upper and lower portions of said base with openings connecting said recesses, a heating plug in said upper recess having contacts extending into said openings, spring contacts in said openings having portions outside of said openings extending in the same direction.

8. In a cigar lighter, an insulating base 30 having longitudinal openings therethrough, a plurality of spring contact elements in said base, and a push pin extending into said base for operating one of said contact elements.

BERNARD F. MULDOON.
